UNITED STATES PATENT OFFICE.

FREDERICK HUGGINS, OF BIRMINGHAM, COUNTY OF WARWICK, ENGLAND.

MACHINERY FOR THE MANUFACTURE OF TUBES.

SPECIFICATION forming part of Letters Patent No. 366,002, dated July 5, 1887.

Application filed December 28, 1886. Serial No. 222,229. (No model.) Patented in Eng'nd May 8, 1886, No. 6,262.

To all whom it may concern:

Be it known that I, FREDERICK HUGGINS, of the firm of William Huggins & Sons, of Birmingham, in the county of Warwick, England, 5 a subject of the Queen of Great Britain, have invented new or Improved Machinery for the Manufacture of Iron and Steel Tubes, (for which I have obtained Letters Patent in Great Britain, No. 6,262, dated May 8, 1886,) of which 10 the following is a specification.

My invention consists of machinery, constructed, essentially, as hereinafter described, for the manufacture of iron and steel tubes, whether welded or open or close jointed.

15 The essential parts of my new or improved machinery are two pairs of rolls and a die having a trumpet-shaped axial opening in it. The said pairs of rolls turn on horizontal shafts working in bearings on the frame of the machine. The rolls at the front of the machine—that is, at that part of the machine at which the strip of iron or steel from which the tube is to be made enters—are of a shape suited to bend the strip of iron or steel passed between them 20 into a trough-shape—that is, semi-tubular, or nearly semi-tubular—one of the said rolls having a groove semicircular in cross-section and the other having a projection or flange semicircular in cross-section, the said flange on one roll working in the groove in the other. The second pair of rolls consists of two similar rolls—that is, rolls each of which has in it a groove semicircular in cross-section, the opposed grooves having the same radius as the 25 finished tube. Between the first and second pairs of rolls the die having a trumpet-shaped axial hole in it is situated, the said die being fixed close to but without touching the first pair of rolls. The wide end or mouth of the bell-shaped opening is turned toward the first 30 pair of rolls. The rolls are geared together with ordinary gearing and are driven by steam or other power. The heated strip to be made into a tube in passing through the first pair of 35 rolls has a trough shape given to it, and in passing through the die the trough - shaped strip is bent or bent and welded into a tubular form and the surface of the tube improved and the tube drawn forward through the die by the 40 action of the second pair of rolls.

I will now proceed to describe, with refer-

ence to the accompanying drawings, the manner in which my invention is to be performed.

Figure 1 represents in side elevation, Fig. 2 in front elevation, and Fig. 3 in plan, machinery constructed according to my invention for the manufacture of iron and steel tubes. Fig. 4 represents in longitudinal section, and Fig. 5 in front elevation, the trumpet shaped die detached.

The same letters of reference indicate the same parts in the several figures of the drawings.

a b are the front rolls, by which a trough or nearly semi-tubular figure is given to the heated strip and the strip forced through the die to the back or finishing rolls. The said rolls *a b* are carried by the shafts *a² b²*.

c d are the back or finishing rolls, by which the drawing or carrying forward of the tube 70 through the trumpet-shaped die is assisted and the surface of the tube improved.

The front pair or troughing rolls, *a b*, consist of a lower roll, *b*, having in it a groove semicircular in cross - section, and an upper roll, *a*, having a projection or flange semicircular in cross-section, as best seen in Fig. 2. The back or finishing rolls, *c d*, are alike in construction, each roll having in it a groove semicircular in cross-section, as seen in Fig. 3. 80 The two pairs of rolls *a b* and *c d* are geared together and driven in the direction indicated by the arrows in Fig. 1 by the arrangement of gearing shown in Figs. 2 and 3.

e is a fixed shaft on which the driving pulley *f* rotates. Connected to and turning with the said pulley is a toothed wheel, *g*, which gears with the toothed wheels *g² g³* on the shafts of the upper rolls, *a c*, of the two pairs of rolls, and the toothed wheels *g² g³* also gear 90 with other toothed wheels on the shafts of the lower rolls, *b d*, of the two pairs of rolls. The distance of the upper rolls, *a c*, from the lower rolls, *b d*, is adjusted by the screws *h h*, acting upon the bearings of the rolls, the said screws 95 being raised and lowered by means of the handle engaged in the heads of the screws. A handle (marked *i*) for the purpose described is represented engaged with the head of one of the adjusting-screws of the upper roll, *a*.

k is the trumpet-shaped die supported in the box or holder *k*, and situated between the

front and back pairs of rolls, *a b* and *c d*, the said box or holder being supported by the part *l*, fixed to the standard of the machine. The wide end of the opening in the trumpet-shaped die *k*² is turned toward the front pair of rolls, *a b*. The trumpet-shaped die *k*² is held in its place by the screw *m*, working in the screw-box *m*² on the standard of the machine, the said screw *m* being raised and lowered by turning the hand-wheel at its top. By raising the said screw *m* the die *k*² may be removed and replaced by a fresh one, or one of a different kind, to suit the tubes being manufactured.

15 The action of the machinery is as follows: The machine is situated near the furnace in which the strips of iron or steel to be made into tubes are heated. The end of a heated strip (marked *n* in Fig. 1) is taken hold of by 20 the workman by means of a pair of tongs and introduced between the first pair of rolls, *a b*. The strip *n*, seized by the rolls *a b*, passes rapidly between them and is bent into a semi-tubular form. Emerging from the first pair 25 of rolls, *a b*, the trough-like strip (indicated in dotted lines in Fig. 1) is forced by the rolls *a b* through the trumpet-shaped axial opening of the die *k*², the axis of the said opening being in a line with the axis of the "eye" of the rolls 30 *a b*. The trough-shaped heated strip of iron or steel in passing through the die *k*² is bent into a tubular form, and on leaving the said die passes between the second pair of rolls, *c d*, the eye of which is in the same line as the 35 axis of the trumpet-shaped opening in the die *k*² and the eye of the first pair of rolls, *a b*. By the action of the second pair of rolls the drawing of the tube through the die is completed and the surface of the tube is improved.

The finished tube passing from the rolls *c d* 40 is marked *p*.

The heated strips of iron or steel may be made by the use of my machinery into welded butt-jointed tubes or into unwelded tubes, commonly called "open-jointed tubes" or 45 "close-jointed tubes." When butt-jointed welded tubes are to be made, the edges of the strip are presented face to face and the width of the strip is such that when it passes through the die *k*² the edges are pressed forcibly together and welded.

In making welded tubes the strips are raised to a welding heat and passed through the machine quickly. When unwelded tubes are to be made, the strips are heated only to 55 bright redness and need not be passed so rapidly through the machine.

Having now particularly described and ascertained the nature of my invention and the manner in which the same is to be performed, 60 I declare that what I claim is—

In machinery for the manufacture of iron and steel tubes, whether welded or open or close jointed, the combination of the troughing and forcing front pair of rolls, *a b*, and 65 the drawing-forward and surface-improving back pair of rolls, *c d*, with the die *k*² between the said pairs of rolls, the axis of the bell or trumpet-shaped opening in the said die being in the same line as the eyes of the two pairs 70 of rolls, for the purpose and substantially as hereinbefore described, and illustrated in the accompanying drawings.

FREDERICK HUGGINS. [L. S.]
